UNITED STATES PATENT OFFICE.

PATRICK H. GREEAR AND JOHN MACKENZIE, OF MINNEAPOLIS, MINNESOTA, ASSIGNEES
TO LEWIS V. PEEK, OF MINNEAPOLIS, MINNESOTA.

AUTOMATIC CIGAR CUTTER AND LIGHTER.

No. 918,532.

Specification of Letters Patent. Patented April 20, 1908.

Application filed June 26, 1908. Serial No. 440,556.

To all whom it may concern:

Be it known that we, PATRICK H. GREEAR and JOHN MACKENZIE, citizens of the United States, residing at Minneapolis, in the county of Hennepin and State of Minnesota, have invented certain new and useful Improvements in Automatic Cigar Cutters and Lighters; and we do hereby declare the following to be a full, clear, and exact description of the invention, such as will enable others skilled in the art to which it appertains to make and use the same.

Our invention has for its especial object to provide an improved device in the nature of a combined cigar cutter and lighter; and to this end it consists of the novel devices and combinations of devices hereinafter described and defined in the claims.

In this improved machine we provide means whereby, when the point of a cigar is pressed against a so-called tripping-plate and through a perforation therein, a cigar cutter will be automatically released and cut off the tip of the cigar, an igniter in the form of a lighted gas jet or burner will be moved against the other end of the cigar, and a pump or air suction device will be set into action to draw air through the cigar and thereby light the same from the said burner.

In the accompanying drawings which illustrate the invention, like characters indicate like parts throughout the several views.

Referring to the drawings, Figure 1 is a view chiefly in side elevation but with some parts broken away and some parts sectioned, showing the improved automatic cigar cutter and lighter. Fig. 2 is a plan view of the same with some parts broken away; and Fig. 3 is a detail in section taken on the line $x^1 x^2$ of Fig. 2. Fig. 4 is a distorted vertical section taken on the irregular line $x^4 x^4$ of Fig. 2; and Fig. 5 is a detail in side elevation, with some parts broken away and some parts sectioned, showing the improved gas burner or igniter.

The case of the machine is made up of a metallic rectangular skeleton frame 1, preferably having glass sides 2, ends 3, and a glass top plate 4, which latter extends only about half the length of the said case. At one end, the metallic top portion of the case is provided with a bearing lug 5 having a sleeve 6 projecting in one direction

and a hollow trunnion 7 projecting in the opposite direction. The sleeve 6 and trunnion 7 are in communication with each other, and the latter is provided with a closed outer end and with a radial circumferentially extended narrow port 8, best shown in Fig. 3.

Mounted to move pivotally on the hollow trunnion 7 is a hub 9 having a sleeve 10, into which is inserted and secured one end of a small metal tube 11 provided, at its free end, with a small discharge passage 65 that opens into the perforated burner hood 12. The sleeve 10 has a radial port 13, which, in the normal or uppermost position of the tube 11, shown by full lines in Figs. 1 and 3, is nearly but not quite out of registration with the port of said trunnion 7.

Pivotedly mounted on the hollow trunnion 7, adjacent to the hub 9 and held against displacement by a screw 14 or other suitable means, a small lever 15 is intermediately pivoted. The upper end of the lever 15 is provided with laterally projecting lugs 16 that embrace the sleeve 10 but are so spaced that the tube 11 and its sleeve 10 are capable of a limited movement without action on said lever 15. In practice, a gas supply tube, preferably in the form of a small rubber tube (not shown) will extend from a suitable gas supply, to the sleeve 6.

Located within the case and secured to the under surface of the metal portion of the top plate thereof is a small metallic box 17. In the top 17 of the box 17 is a quite small perforation 18, and journaled in the bottom plate of said box, eccentric to the said perforation 18, is a small upright shaft 19. The shaft 19, at its upper end, carries a knife 20 that is arranged to rotate in close engagement with the under surface of the top 17 of said box 17 and move across said perforation 18. At its lower end, the shaft 19 carries a bevel gear 21 that meshes with a pinion 22 of a short countershaft 23 journaled in a suitable bearing 24, depending from the box 17. This shaft 23 also carries a large spur gear 25 that meshes with a spur pinion 26 carried by the armature shaft 27 of a small electric motor 28, diagrammatically shown in Figs. 1 and 2. The shaft 23 further carries an eccentric 29 in which works the upper end of an eccentric rod 30, which eccentric rod actuates the movable member of an air pump. As shown, this air pump is made

up of a cylindrical body 31 formed integral with the bottom plate of the case, and a movable member in the form of a diaphragm 32 secured to said cylindrical body 31. In 5 this instance, the lower end of the crank or eccentric rod 30 is, pivotally connected to a leg 33 secured to the central portion of the diaphragm 32. An air inlet passage 34 opens into the cylindrical body 31, and an air outlet passage 35 leads from the said body 31. A check valve 36 in the passage 34 permits air to flow into the cylinder 31, but checks reverse flow, while a check valve 37 in the passage 35 permits air to flow outward from said cylinder, but checks a reverse flow through the said passage 35. The sleeve-like upper end of the air inlet passage 34, as shown, is connected, by an air tube 38, to a depending tubular stem 39 which opens from 20 the bottom of the box 17. It may be here stated that the said box 17 is closed except through the perforation 18 and through the tubular stem 39.

A so-called tripping plate 40 is secured to 25 one arm of a bellcrank lever 41, which latter is pivotally connected to the top of the case 1, at 42. At its intermediate portion, this tripping plate 40 is formed with a downwardly tapered or bell-mouthed perforation 43, into which the tip end of the cigar is 30 adapted to be inserted in a position directly over the perforation 18 in the top plate 17 of the box 17. The top of the case 1 is cut away so as to permit the depending hub portion 35 of the tripping plate 40 to pass therethrough when the said tripping plate is depressed to its limit, as indicated by dotted lines in Fig. 1. Normally the tripping plate 40 is held in its raised position shown by full lines in Fig. 1, by means of a coiled spring 44 attached to the depending arm of the bellcrank 41 and to the box 17. The lower arm of the bellcrank 41 is connected, by a rod 45, to the depending arm or end of the lever 15. To form a contact operating shoulder, the rod 45 is bent, as shown at 46, (see Fig. 1).

Rigidly secured to lugs 47 and 48 (see Fig. 2) on the top of the case is a pair of spring 50 contacts 49 and 50, respectively, the former of which is adapted, when released, to spring into engagement with the latter. Normally, however, the contact 49 is engaged by an insulation 51 carried by the crooked portion 55 or shoulder 46 of the rod 45, and is held out of engagement with the contact 48, as shown in Figs. 1 and 2.

The numerals 52 and 53 indicate leads to the motor 28; and as shown, said lead 53 includes the normally separated contacts 49 and 50, so that the motor circuit is normally broken and the motor cut out from the source of supply.

At one side the box 17 is provided with a depending hopper-like sleeve 54 to which a

catch box 55, preferably of cylindrical form, is detachably secured for the purpose of catching the cigar tips cut by the knife 20.

Operation: A cigar to be cut and lighted is placed in an upright position, with its tip entered into the funnel-shaped perforation 43 of the tripping plate 40, and the said tripping plate is forced downward to its limit, indicated by dotted lines in Fig. 1. The first effect of thus moving the tripping plate downward is to enter the tip of the cigar through the perforation 18 in the top plate 17 of the box 17. Said downward movement of the tripping plate, acting through the bellcrank 41 and rod 45, accomplishes two things, to-wit: It permits the contact 49 to engage the contact 50, thereby closing the motor circuit and throwing the motor into action, and it rocks the lever 15, causing the gas tube 11 to move downward until its head 12 engages the upper end of the cigar 2. The maximum movement thus imparted to the tube 11 will be sufficient to allow the head 12 to move downward into engagement with a short cigar; but by a long cigar the engagement of the head 12 with the upper end thereof will intercept the downward movement of said head 12 and tube 11, before the lever 15 has completed its movement. This variation in movement, as already indicated, being permitted by the lugs 16. When the motor is thrown into action it operates the pump and rotates the cigar cutter or knife 20. The initial rotation of the knife will cut off the tip of the cigar, which tip falls into the catch box 55; and the pump, when thrown into action, draws air downward through the cigar into the box 17, and from thence through the tube 38 and conduit 34 into the cylinder 31, and from the cylinder 31 discharges the air through the discharge passage 35. Thus it will be seen that by this device the tip of the cigar is cut, the burner is positioned at the upper end of the cigar, and air is drawn through the cigar, thereby lighting the same. When the arm 11 and head 12 are in their uppermost positions, only a very small amount of gas will be discharged at the burner. In fact, only enough to maintain the smallest possible flame; but when said tube and head are moved downward, the port 8 in the tubular trunnion 7 will be opened up to a much greater extent, so as to afford a good flame at the time the cigar is being lighted. When the lighted cigar is removed from the tripping plate, the spring 44 will restore all of the movable parts to their normal position and the motor circuit will be again broken, so that the motor will be stopped. The motor is, therefore, used only while the cigar is being cut and lighted.

So far as the broad idea of our invention is concerned, any means for drawing air through the cigar; or, in other words, any

kind of an air suction device, may be employed, but we preferably employ an electric motor and a pump. A pump, as distinguished from a fan or blower, has a positive action and produces a succession of pulsations which better serve to light a cigar than a continuous suction or draft.

What we claim is:

1. In a device of the kind described, the combination with a cigar lighter and a cigar cutter, of an air suction device for drawing air through a cigar while in position for cutting, a motor for actuating said cutter and air suction device, and a trip which when operated throws said motor into action and moves said lighter against the end of the cigar.
2. In a device of the kind described, the combination with a cigar cutter and lighter, of an air suction device including a pump with connections for drawing air through the cigar while in position for cutting, a motor for actuating said cutter and said pump, and a trip adapted to be engaged by the cigar and operative to throw said motor into action and to move said lighter against the end of the cigar which is to be lighted.
3. In a device of the kind described, the combination with a cigar cutter and a cigar lighter, of an air suction device with connections for drawing air through the cigar while in position for cutting, an electric motor for actuating said cutter and said air suction device, and a trip with which the cigar is engageable, operative to close the motor circuit and to move said lighter against the end of the cigar to be lighted.
4. In a device of the kind described, the combination with a cigar cutter and a cigar lighter, of an air pump with connections for drawing air through the cigar while in position for lighting, an electric motor for actuating said pump and cutter, and a trip operative to close the motor circuit and move said lighter against the end of the cigar to be lighted.
5. In a device of the kind described, the combination with a rotary cigar cutter and an air pump with connections for drawing air through a cigar while in position for cutting, of an electric motor for driving said cutter and pump, a cigar lighter, and a tripping plate located above said cutter and

below said lighter, having a perforation through which a cigar may be inserted and positioned for cutting, the said tripping plate having connections for closing the motor circuit and for moving said lighter downward onto the upper end of the cigar.

6. In a device of the kind described, the combination with a suitable framework and a box supported thereby, said box having a perforation through which the tip of the cigar may be inserted, a knife within said box, a motor with connections for operating said knife, an air pump operated by said motor and connected to the outlet of said box, a cigar lighter, a tripping plate mounted above said box, and a connection from said tripping plate to said lighter for moving the same against the upper end of the cigar and for throwing said motor into action.

7. In a device of the kind described, the combination with a cigar cutter, a cigar lighter, and an air suction device arranged to draw air through the cigar while in position for cutting, of a box inclosing said cutter and provided with a detachable catch box, a motor for actuating said cutter and suction device, and a trip with connections for actuating said motor and for moving the said lighter against the end of the cigar.

8. In a device of the kind described, the combination with a cigar cutter, of an air suction device arranged to draw air through the cigar while in position for cutting, and a motor for actuating said cutter and suction device, of an igniter comprising relatively fixed and movable gas conducting tubes having coöperating ports, said movable tube having an igniting head at its free end, and a tripping device comprising a pivoted tripping plate with a perforation through which the cigar may be projected to said cutter, and a connection from said tripping plate arranged to actuate said motor and to move said pivoted gas tube but permitting a limited independent movement of said gas tube.

In testimony whereof we affix our signatures in presence of two witnesses.

PATRICK H. GREEAR.
JOHN MACKENZIE.
